UNITED STATES PATENT OFFICE

92,510

DESIGN FOR A PROJECTION LAMP

Clarence S. Ashcraft, Los Angeles, Calif.

Application April 13, 1934, Serial No. 51,394

Term of patent 14 years

To all whom it may concern:

Be it known that I, CLARENCE S. ASHCRAFT, a citizen of the United States, residing at Los Angeles, in the county of Los Angeles and State of California, have invented a new, original, and ornamental Design for a Projection Lamp, of which the following is a specification, reference being had to the accompanying drawings, forming part thereof.

Fig. 1 is a side elevational view.

Fig. 2 is a front elevational view.

Fig. 3 is a rear elevational view.

Fig. 4 is a plan view, and

Fig. 5 is a perspective view showing the front, side and top of the device.

I claim:

The ornamental design for a projection lamp, as shown.

CLARENCE S. ASHCRAFT.
